LOUD-SPEAKER

Carleton T. Weibler, St. Charles, Ill., assignor to
 Operadio Manufacturing Co., St. Charles, Ill.,
 a corporation of Illinois

Application October 26, 1945, Serial No. 624,660

18 Claims. (Cl. 181—31)

1

This invention relates to a loud speaker and particularly to a loud speaker for use in exposed locations subject to wind pressures.

Loud speakers of the type having a conical diaphragm cannot be used where any wind may strike the diaphragm. Irrespective of the driving means for operating the diaphragm, the diaphragm itself is generally driven by vibrating the same along the cone axis with respect to a normal rest position. Where a speaker is disposed in a location subject to wind pressure, the great area presented by a cone diaphragm results in the diaphragm and driving means being forced away from the normal rest position.

Thus, as an example, in the case of a dynamic speaker having an annular air gap with a voice coil assembly therein, the voice currents cause the assembly to vibrate back and forth from its normal rest position. Depending upon the polarity of the voice currents, the movement of the assembly and diaphragm will either be in the forward or reverse direction from the rest position. If, by virtue of wind pressure, the diaphragm and voice coil assembly is forced to assume a different position as a rest position, then total or partial inoperativeness may result.

A further drawback to the use of a speaker in exposed locations subject to wind resides in the possible damage to which the diaphragm may be subjected by air-borne dust and grit. While weather-proofing diaphragms is well known, nevertheless sharp particles of grit and sand blown by wind may cause surface scratches in the diaphragm and expose the diaphragm interior to undesirable weathering influences. In addition, the abrasive action of air-borne dust and sand may actually weaken the diaphragm to the point where its characteristics are entirely different from the normal desired characteristics and, in some instances, total destruction of the diaphragm as such may occur.

In accordance with the invention herein, a shielding means is provided for the cone diaphragm of a loud speaker. This shielding means is so designed as to protect the diaphragm against wind and air-borne dust. The shielding member has means associated therewith so designed that the coupling characteristics between the conical diaphragm and atmosphere are substantially unaffected so that speaker performance in terms of sound radiation and efficiency remain substantially unchanged.

The invention further provides means for preventing any substantial change in air pressure on the exposed diaphragm surface arising out of

2

the action of any wind blowing against the shielding system. Thus, a structure embodying the invention guides the air so that smooth deflection occurs without an adverse effect upon speaker performance. The guiding of the air is accomplished in such a manner that air-borne dust and grit is centrifugally eliminated and prevented from reaching the diaphragm air space. The air space at the exposed diaphragm surface is thus maintained in a substantially static condition as far as any wind effects are concerned so that it may respond efficiently to vibrations of the diaphragm.

A structure embodying the invention additionally provides convenient protection against rain and prevents any water from impinging directly on the diaphragm.

In its more general form, the invention provides an assembly which may be applied to or removed from the speaker as a unit or which may be incorporated with the speaker to form a complete speaker unit which may be operated in exposed locations. The structure added to the speaker consists generally of a rigid baffle structure and enclosing air relief ring. The baffle structure as a whole has obverse and reverse faces, the two faces terminating in a generally circular mounting portion or rim. The baffle structure is preferably symmetrical with respect to an axis, this axis being coincident with the diaphragm axis of the speaker in the normal use of the baffle structure. The baffle structure is so disposed that the reverse face is spaced in opposed relation from the diaphragm of the speaker. Thus, the obverse face of the baffle structure may be seen from the front of the entire speaker including the baffle structure.

The baffle structure as a whole is of rigid material and has the reverse face shaped in the general form of a cone generally congruent to the speaker cone with which it is to be used. The projected area of the speaker diaphragm is preferably equal to the projected area of the baffle structure. By proper design and shaping of the baffle surfaces, air blowing toward the speaker diaphragm strikes the obverse baffle surface and is deflected toward the mounting portion. The relief ring structure provides a passage for such deflected air outwardly toward the atmosphere, the air stream path being generally straight enough so that dirt and dust deflected by the baffle will follow the air out of the speaker.

In order to prevent aspiration of the air between the speaker diaphragm and reverse face of the baffle structure, the relief ring is so de-

signed as to provide for the creation of some back pressure. This back pressure is generated in an annular space and maintains a substantially constant air pressure on the diaphragm face under wide changes in wind pressure.

The baffle structure itself may take on a wide variety of forms, and the relief ring may also take on a wide variety of forms. The two together are rigidly supported with respect to each other and may form an assembly which may be added to a speaker as a unit or which may be added separately to the speaker and all the parts rigidly maintained to form a stable structure.

For a more complete description of the invention, reference will now be made to the drawings wherein an exemplary embodiment of the invention is shown, it being understood that the invention itself is susceptible to many modifications.

Referring to the drawing,

Figure 1 is an elevation with parts broken away of a speaker having an assembly embodying the invention attached thereto.

Figure 2 is a detail of the grille.

A baffle structure generally indicated by numeral 10 and made of any suitable rigid material such as stamped sheet metal has generally conical reverse face 11 and wind deflecting obverse face 12. In its simplest form, baffle structure 10 may consist of two sheet metal members 13 and 14 having mounting rims 15 and 16 respectively. Sheet metal member 13 may be shaped to provide reverse face 11, while member 14 may be bulged out to form obverse face 12. While it is not necessary that obverse face 12 be convex, it is preferred to have such a shape to provide desirable wind deflecting action. In its simplest form, metal member 14 may be shaped to form a portion of a sphere so that obverse face 12 will have a spherical curvature.

Mounting rims 15 and 16 are preferably shaped so that they are flat and may be disposed against each other to form a mounting portion for the baffle structure. Gasket 17 may be disposed between the opposed faces of mounting rims 15 and 16 to provide an air-tight baffle structure. It is understood that the mounting portion for the entire structure may be thicker if desired.

Annular relief ring 19 is disposed around mounting rims 15 and 16 and spaced therefrom to provide annular air space 20 between the inside of relief ring 19 and mounting portions 15 and 16. Annular relief ring 19 may be formed of sheet metal or any other solid material provided with a large number of apertures. It may also be formed of woven wire or the like. Relief ring 19 preferably forms part of grille 22 extending over the front of the baffle structure, namely obverse face 12. Grille 22 may be formed of the same material as relief ring 19. The grille is provided to prevent dirt, bugs and other relatively large objects from getting into the speaker structure. Grille 22 may have any desired shape and is here shown as flat.

Spaced from but enclosing relief ring 19 is rain guard 23. This is formed of solid material such as sheet metal and is disposed against the peripheral portion of grille 22. To prevent rattling, gasket 24 is disposed between the rain guard and grille. As is clearly evident from the drawing, rain guard 23 clears relief ring 19 so that outside air may readily reach relief ring 19. Preferably rain guard 23 extends down to the bottom of relief ring 19.

Drip guard 26 in the form of an annular ring

is provided, this guard having upstanding flange 27. The guard and flange are of solid material such as sheet metal with the flange disposed immediately against a portion of the relief ring. 5 As shown, flange 27 is inside of a part of relief ring 19 although the positions may be reversed.

It will be noted that flange 27 has its free edge 28 so disposed with respect to the mounting rims of the baffle structure that the portion of relief ring 19 which communicates with the atmosphere is substantially in lateral alignment with the deflecting portion of the baffle structure. Any air deflected from obverse face 12 may, therefore, pass straight through relief ring 19.

15 The entire assembly may be maintained as a unit by suitable means disposed at circumferentially spaced points along mounting rims 15 and 16. As shown, clamping regions are provided, each one having eyelet 30 threaded through suitably aligned apertures in the gaskets, rain guard, grille and drip guard. To maintain the parts in the position shown, spacing sleeves 32 and 33 may be provided on opposite sides of the baffle structure mounting portion. Gasket 34 may be dis-

20 posed against drip guard 26, this gasket being on the outside of the baffle assembly. Gasket 34 thus presents an annular surface which may be considered a mounting surface for the entire assembly.

25 30 The entire assembly may be secured to a speaker by bolting the same. Thus, speaker 36 has annular mounting portion 37 against which gasket 34 may be fitted. Annular mounting portion 37 is generally formed as a sheet metal spider or basket construction 38. Annular mounting portion 37 has secured thereto the large end of conical diaphragm 40. It is preferred to have reverse face 11 generally congruent to conical diaphragm 40 with the two being substantially of equal size.

35 40 The distance between the assembly mounting portion determined by gasket 34 or ring 27, if no gasket is used, and mounting rims 15 and 16 of the baffle structure will generally determine the spacing between opposed face 11 and diaphragm 40. The air space thus formed, generally indicated by numeral 41, terminates in a circumferential area 42 generally extending between the peripheral edges of face 11 and diaphragm 40.

45 50 In general, area 42 may be considered as a cylindrical surface tangent to sleeves 32, 33. It is preferred to so proportion air space 41 that the opposed diaphragm and baffle faces are generally parallel. It is also preferred to so proportion air space 41 that circumferential area 42 is substantially equal to the area of diaphragm 40. Thus, air waves generated by diaphragm 40 will tend to move out of the air space toward area 42 and the coupling between air space 41 and annular space 20 will be such as to minimize interference. From annular region 20, air waves generated by diaphragm 40 continue around mounting rims 15 and 16 of the baffle and pass through grill 22 to the front of the speaker. At a short distance away from the front of the entire speaker, it is found that the speaker characteristics with or without the baffle assembly remains substantially the same.

55 60 Conical diaphragm 40 differs somewhat from reverse face 11 at the small ends. Many speakers have dust cap 43, this generally having a spherical curvature. Dust cap 43 is part of voice coil assembly 44, this assembly, as is well known, providing a cylindrical voice coil. The voice coil assembly operates in an annular air gap of the

usual magnetic structure. The magnetic structure may be either of the permanent or electro-magnetic type, all of which are well known in the art.

The small end of conical diaphragm 40 is supported on corrugated disc 45 whose outer edge may be rigidly supported by spider 38. Inasmuch as the construction of loud speakers is well known in the art, no further details such as voice coil leads and magnetic structure need be given.

Mounting portion 37 of the speaker may have a plurality of apertures therethrough registering with eyelets 30. Bolts 46 passing through the eyelets and mounting portion 37 of the speaker will retain the speaker and assembly rigid. The entire speaker may be enclosed in a suitable container.

It is evident that eyelets 30 may be omitted, and that the baffle structure assembly may be added to the speaker as individual parts rather than as a complete assembly, and the whole speaker as such maintained rigid by bolts, eyelets or any other means.

It is clear that a baffle structure embodying the invention permits of speaker operation under wind conditions. Rain guard 23 may be omitted if desired. Similarly, grille 22 may be omitted. Wide variations and changes in mechanical details of the baffle structure, support and spacing means may be made without departing from the spirit of the invention.

What is claimed is:

1. An assembly for use with a conical diaphragm type of speaker for attachment thereto to permit speaker operation in exposed locations, said assembly comprising a baffle structure having obverse and reverse faces and a mounting portion all symmetrical with respect to an axis, said reverse face having a generally conical shape, an annular apertured member enclosing said structure at the mounting portion but spaced from said mounting portion to provide an annular air space, means for rigidly supporting said annular apertured member and baffle structure, said assembly being adapted to be disposed so that the axis of said baffle is coincident with the diaphragm axis and the reverse face is spaced from but opposed to said diaphragm, said baffle structure covering the entire diaphragm whereby air and dirt which would otherwise impinge on said diaphragm are deflected.

2. An assembly for use with a conical diaphragm type of speaker and adapted to be readily attached thereto to permit speaker operation in exposed locations, said assembly comprising a baffle structure generally symmetrical to an axis coincident with the diaphragm axis when said assembly is disposed on a speaker, said baffle structure having a peripheral mounting portion and a generally conical reverse face and a wind deflecting obverse face, said two faces being symmetrical with respect to said axis, an annular member surrounding said baffle structure at the mounting portion, said annular member being spaced from said mounting portion to provide an annular air space, said annular member being apertured to provide air communication with the atmosphere and means for maintaining said annular member and baffle structure in assembled relation, said baffle structure when mounted being adapted to have said reverse face projecting inwardly toward said conical diaphragm and spaced therefrom.

3. An assembly for use with a conical diaphragm type of speaker and adapted to be read-

ily attached thereto to permit speaker operation in exposed locations, said assembly comprising a baffle structure symmetrical with respect to an axis and having a circular mounting portion symmetrical with respect to said axis, said baffle structure having a reverse cone surface adapted to be disposed in proximity to a speaker diaphragm, said baffle structure having an obverse wind deflecting surface, an annular ring shaped member surrounding said mounting portion and spaced therefrom to form an annular air space between the two, a plurality of supporting means spaced along said mounting portion and engaging said annular ring for maintaining the two in assembled relation, the intervening space along said mounting portion between adjacent supporting means being otherwise clear, said annular member being apertured to provide air communication between said annular air space and outside atmosphere.

4. The structure of claim 3 wherein said annular apertured member has a portion thereof disposed over said obverse face of said baffle structure, said covering portion being apertured.

5. An assembly for use with a conical diaphragm type of speaker to permit operating the same in windy locations, said assembly comprising a baffle structure having a cone and baffle member each with a mounting rim, said baffle and cone bulging outwardly away from each other to provide obverse and reverse faces for said baffle structure and having their rims sealed together, an annular apertured member disposed around said mounting rims and spaced therefrom to define an annular air space, said apertured member having a mounting portion lying in a plane parallel to the plane of said baffle structure mounting rims and laterally displaced therefrom on the baffle side, a mounting ring parallel to the mounting portion of said apertured member but on the other side of the mounting rims for said baffle structure, a plurality of spacing sleeves disposed at points spaced along the length of and on opposite sides of said baffle mounting rims and extending toward the mounting portion and mounting ring, and means passing through said sleeves for maintaining said assembly in rigid relation.

6. The structure of claim 5 wherein said apertured annular member has a portion also apertured and spaced from and over-lying the obverse space of said baffle structure.

7. An assembly for use with a conical diaphragm type of speaker to permit operating the same in windy locations, said assembly comprising a baffle structure having a cone and baffle member each with a mounting rim, said baffle and cone bulging outwardly away from each other to provide obverse and reverse faces for said baffle structure and having their rims sealed together, an annular apertured member disposed around said mounting rims and spaced therefrom to define an annular air space, said apertured member having a mounting portion lying in a plane parallel to said baffle structure mounting rims and laterally displaced therefrom on the baffle side of said rims, a mounting ring lying in a plane parallel to said mounting portion and disposed on the other side of said mounting rims, said mounting ring having a solid flange-like portion forming the outer wall of a portion of the annular air space on the cone side of the mounting rims, spacing means on opposite sides of said mounting rims and extending toward said mounting portion and mounting ring respective-

ly, said spacing means being localized at regions spaced along the mounting rims so that said annular air space has substantially free communication with the air on the two faces of said baffle structure, and means for maintaining said mounting rims, ring and portion in rigid relation.

8. The structure of claim 7 wherein said last-named maintaining means comprises eyelets passing through said speakers.

9. The structure of claim 7 wherein a solid annular member disposed around but spaced from said apertured member is provided, said solid member having a mounting portion disposed to lie against the mounting portion of said apertured member.

10. An assembly for use with a conical diaphragm type of speaker to permit operating the same in windy locations, said assembly comprising a baffle structure and having a cone and baffle member each with a mounting rim in a plane perpendicular to the cone axis, said baffle and cone bulging outwardly away from each other to provide obverse and reverse faces for said baffle structure and having their rims disposed against each other, an annular apertured member disposed around said mounting rims and spaced therefrom to define an annular air space and having an apertured grille portion in front of said obverse face, said apertured member having a portion thereof forming a mounting portion lying in a plane parallel to the plane of said baffle mounting rims and laterally displaced therefrom on the baffle side of said rims, a mounting ring lying in a plane parallel to said apertured mounting portion but on the other side of said mounting rims, said ring having an upstanding flange portion extending toward the plane of said mounting rims and terminating near said plane, said flange forming an enclosing wall for part of said annular air space, sleeves extending from said mounting rims on opposite sides toward said mounting portion and ring respectively, said sleeves being spaced circumferentially along said mounting rims, and means passing through said sleeves for maintaining the entire assembly in rigid relation.

11. The structure of claim 10 wherein said last-named maintaining means comprises eyelets passing through said sleeves.

12. A loud speaker comprising a conical diaphragm, a baffle structure for said diaphragm, said baffle structure having a conical reverse face and having an obverse face, means for mounting said baffle structure so that the reverse face is spaced from and symmetrically disposed with respect to the outer diaphragm surface, an apertured enclosing member surrounding the edge of said baffle structure and spaced therefrom to define an annular air space joining the air spaces on the opposite faces of said baffle structure, and means for maintaining said baffle structure, apertured member and cone diaphragm in assembled relation.

13. The structure of claim 12 wherein said cone face of said baffle structure is generally congruent to said cone diaphragm and wherein the spacing between the two is so chosen that the transverse

area at the outer edge of the air space between the diaphragm and obverse face is substantially equal to the diaphragm area.

14. A loud speaker including a cone diaphragm having a mounting rim at the large end of the cone, a baffle structure having a cone and a baffle member disposed in back-to-back relation, said structure having a mounting rim spaced from but overlying the mounting rim at the diaphragm, 15 said baffle structure having the cone spaced from said diaphragm, an apertured member enclosing said baffle mounting rim but spaced therefrom to provide an annular air space, said apertured member having a mounting portion over-lying the baffle mounting rim but spaced therefrom on the front side, said apertured portion extending in front of said baffle structure to provide a grille, and means disposed at spaced points along said rim and portions for maintaining the structure intact.

20 15. The structure of claim 14 wherein a solid annular member is provided around said apertured member and spaced therefrom to prevent rain from entering into said speaker along the side.

25 16. The structure of claim 14 wherein the spacing between the diaphragm and cone is such that the peripheral area of this space is substantially equal to the area of the diaphragm.

30 17. A loud speaker including a cone diaphragm having a mounting rim at the large end of the cone, a baffle structure having a cone and baffle member each with a mounting rim in a plane perpendicular to the axis of the diaphragm, said 35 baffle and cone bulging outwardly away from each other to provide obverse and reverse faces respectively for said baffle structure and having their rims disposed against each other, the reverse face being opposite and spaced from said 40 cone diaphragm, the spacing being such that the peripheral area is equal to the diaphragm area, an annular apertured member disposed around said mounting rims and spaced therefrom to define an annular air space, said apertured member having a portion thereof forming a mounting portion lying in a plane parallel to the plane of said baffle mounting rims and laterally displaced therefrom on the baffle side of said rims, a mounting ring lying in a plane parallel to said apertured 45 mounting portion but on the other side of said baffle mounting rims, sleeves extending from said baffle mounting rims on opposite sides toward said mounting portion and ring respectively, said sleeves being spaced circumferentially along said 50 mounting rims, said mounting ring being disposed against the mounting rim of the speaker, and means passing through said sleeves for maintaining the entire assembly in rigid relation.

55 18. The structure of claim 17 wherein said mounting ring has an upstanding flange portion extending toward the plane of said baffle mounting rims and terminating near said plane, said flange forming an enclosing wall for part of said annular air space, and wherein a solid annular member is provided spaced from but enclosing said apertured member.

CARLETON T. WEIBLER.
